[57] **CLAIM**

The ornamental design for a cushion pad for intra-oral X-ray films, as shown and described.

DESCRIPTION

FIG. 1 is a top and front perspective view of a cushion pad for intra-oral X-ray films showing my new design, with the broken-line showing of the X-ray film packet being for illustrative purposes only and forming no part of the claimed design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and

FIG. 7 is a left side elevational view thereof.
